UNITED STATES PATENT OFFICE

117,777

DESIGN FOR A COMBINED DRILL PRESS AND FRAME

Waldemar Ayres, New York, N. Y.

Application April 12, 1939, Serial No. 84,227

Term of patent 14 years

To all whom it may concern:

Be it known that I, Waldemar Ayres, a citizen of the United States, residing at 509 West 110th Street, New York, in the county of New York and State of New York, have invented a new, original, and ornamental Design for a Combined Drill Press and Frame, of which the following is a specification, reference being had to the accompanying drawing, forming part thereof.

Figure 1 of the drawing is a perspective view of a combined drill press and frame embodying my new design, and

Figure 2 is a view in side elevation from the opposite side.

I claim:

The ornamental design for a combined drill press and frame, substantially as shown.

WALDEMAR AYRES.
